CLAIM

The ornamental design for a display stand as shown and described.

DESCRIPTION

FIG. 1 is a top, front and left side perspective view of a display stand showing my new design;

FIG. 2 is a top, rear and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion 9 in FIG. 1;

FIG. 10 is an enlarged view of portion 10 in FIG. 2; and, FIG. 11 is an enlarged view of portion 11 in FIG. 2.

The evenly dashed broken lines in FIGS. 1-8 and 10-11 illustrate portions of the display stand that form no part of the claimed design.

The unevenly dashed broken lines in FIGS. 1-2 and 9-11 illustrate the boundary of the enlarged views and form no part of the claimed design.

1 Claim, 11 Drawing Sheets
